UNITED STATES PATENT OFFICE.

HUGH IORWERTH ROBERTS, OF LIVERPOOL, ENGLAND.

BALING-PRESS.

1,318,110.

Specification of Letters Patent.

Patented Oct. 7, 1919.

Application filed December 26, 1917. Serial No. 208,987.

To all whom it may concern:

Be it known that I, HUGH IORWERTH ROBERTS, subject of the King of Great Britain and Ireland, and resident of Liverpool, in the county of Lancaster, England, have invented certain Improvements in Baling-Presses, of which the following is a specification.

This invention relates to improvements in presses for baling hay, straw, cotton, wool or other materials and has particular reference to portable horizontal presses, though the presses may be fixed, if required, in any position. The improvements are designed to enable the press to follow any ordinary type of perpetual press and to allow of the material so pressed in the latter being compressed to a greater density in the new arrangement of press so that such material will occupy less space. A further object is to enable the feeder portion of the perpetual press to be attached to the new construction of press and so constitute one press instead of two.

My invention comprises generally an improved construction of supporting frame; an improved arrangement of receiving and pressing boxes adapted to revolve about a central axis for the purpose of receiving the material to be compressed and to allow of its compression; an improved press head arrangement for the boxes; an improved arrangement for guiding the follower and toggle levers; an improved arrangement of follower; an improved arrangement of toggle levers for operating the follower; means for actuating the toggle levers; devices for centralizing and holding the press boxes in the required position during compression and withdrawal of the press head; means for automatically stopping the feed when a predetermined density has been reached; the combination with the revolving press boxes of a hydraulic cylinder and ram and means for exerting pressure on the ram together with other details which will be hereinafter referred to.

My invention will be fully described with reference to the accompanying drawings in which,

Figure 1, is a side elevation of a press constructed in accordance with my invention.

Fig. 2, plan of same partly in section,

Fig. 3, elevation of the gearing end partly in section,

Fig. 4, side elevation of a press with hy-

draulic attachment showing modified form of bearing arrangement for the press boxes,

Fig. 5, plan of same.

Fig. 6, side elevation of a complete press with certain modified arrangements showing also a known feeder arrangement or perpetual press,

Fig. 7, plan of same,

Fig. 8, plan of the press boxes shown in Fig. 7, to an enlarged scale indicating the means for centralizing and locking the boxes in compressing position,

Fig. 9, end elevation of same, and

Fig. 10, a modified arrangement of means for centralizing the press boxes.

In accordance with my invention and referring particularly to Figs. 1 to 3, I provide a main frame *a* of any suitable construction, though I find it convenient to make it of channel section adapted to support the pressing boxes, the toggle or other mechanism and follower and means for actuating same. The frame in the portable construction is supported upon road wheels *b*.

At the forward end of the frame *a* I locate the pressing boxes *b*¹ of which there are two in axial line with each other, though I may employ more than two if convenient or necessary. The boxes *b*¹ are arranged to be capable of rotating horizontally about a vertical axis *c*, though where the conditions are suitable they may rotate about a horizontal axis. In either case the axis *c* may be journaled in the main frame *a* and have the boxes *b*¹ suitably secured to it or they may be rotated about a fixed axis or upon circular rails adapted to be carried on the frame. In Figs. 1 to 3 I have shown the axis *c* as being fixed to the main frame and mounted on this between the upper and lower frame members is a rectangular or polygonal casting *d* each flat side of which in conjunction with the shaft *c* forms the head of the press against which a lashing plate *e* is placed or fixed. The body of each press box extends from the casting to which it is securely fixed and is open at the outer end *f* for the reception of the material to be further compressed and a follower lashing plate *g*, Figs. 4 and 5 and 6. The sides and top or bottom of each press box are provided with doors *h* preferably but not necessarily hinged as at *i* to the press head *d* to allow for the compressed material being lashed and for its discharge either at the top or bottom of the box. The doors may be secured in posi-

tion.

tion by catches of any convenient construction but the form of catch which I prefer consists in each case of an open frame *j* pivoted on a pin *k* at its open end carried by 5 the press box. In conjunction with the frame I employ a central link *m* pivoted at its lower end to the door *h*, the upper end of the link having pivoted to it by pin *o* a hand lever *p* adapted to bear upon the 10 cross bar of the frame *j* when the door is held in the locked position. I combine with this arrangement which is shown more clearly in Fig. 8, means for holding the successive charges of material to complete one charge, 15 within the press box as the follower recedes and to insure that such holding means are removed out of the way of the follower prior to its receding from the box, the arrangement being such that the holding means are 20 bound to be withdrawn before the press box doors can be opened for the discharge of the bale. To this end I employ links *p*¹ pivoted to the forward portion of the press box at *q* such links having double inclined projec- 25 tions *r* formed on them to pass within the box. The projections *r* normally project inside the box and are moved outwardly by the follower in the act of pressing the material, and are subsequently moved inwardly 30 by any approved means. In connection with the links, I employ double armed levers *s* having a long and short arm, connected to the links by pins *t*, the long arms *t*¹ projecting over the doors *h* when the latter are 35 closed. Before the doors can be opened it is necessary to pull the long arms of levers *s* outwardly so that their short arms *t*² bear against the press box and force the links and their projections outwardly and hold 40 them in that position. The press box doors can then be opened by operating the catches in the opposite way to that described.

The press boxes *b*¹ are built up on a subsidiary frame *u* which may be arranged 45 close to the lower or upper member of the main press frame *a*, the opposite side of the box to the subsidiary frame being of skeleton formation such as might be constituted by bolts *v*, bars or rails connected to uprights 50 *w* from the subsidiary frame *u* so as to leave space between the parts for discharging the bale. In general practice the frame work referred to as well as the main frame is substantially of skeleton formation to allow of 55 doors being opened if required at every side of the press box.

The press boxes may be turned around by hand so as to bring one box into line with the feeder part *w*¹ of the perpetual press 60 shown in Figs. 6 and 7 and the other in line with the new press follower *x* Figs. 1 to 3 or with the hydraulic ram *y* in Figs. 4 to 6, thus enabling one box to be charged with material from the perpetual press while the 65 material in the other is subjected to addi-

tional compression. The means for centralizing and holding the press boxes in position will be hereinafter described.

The mechanism shown in Figs. 1 to 3 for compressing the material comprises a follower *x*, toggle lever mechanism and means for actuating the toggle levers. For this purpose I employ a horizontal screw 3 having right and left handed threads with a nut 4 mounted upon each threaded portion. 70 The outer ends of each pair of toggle levers (there are two pairs) are coupled to the nuts while their inner ends are connected to vertical pins 5 and 14 carried respectively by the follower *x* and the main press frame *a*. The 80 toggle levers are moved inwardly toward the axial line of the press and outwardly from that line by a spur wheel 6 fixed upon the center of the screw shaft and actuated by carrier pinions 7 carried upon links 8 85 centered respectively upon the screw shaft or upon the screw and driving shafts 9 the latter having fixed upon it a driving pinion 10 engaging with one of the carrier pinions. The driving shaft 9 is mounted in bearings 90 on the main frame *a* and is driven from a portable engine or from any other convenient source. The arrangement of carrier pinions referred to is to enable them to be kept in gear with themselves and with the driving 95 pinion and wheel as the toggle levers open and close. The screw 3 may be driven direct by hand or by animal-operated means conveniently geared thereto under the frame.

The two pins or studs 5 connecting the 100 toggle levers to the follower *x* serve to support the overhanging weight of the latter and toggle levers for which purpose they are secured at their lower ends in a base 12 105 slideable in or upon the main press frame *a*, friction being reduced by the employment of a roller or rollers 13 at the rear end of the base running upon the main frame *a*. This roller also guides the follower and toggle arms. The outer pair of toggle arms are 110 pivoted on pins 14 carried by the main frame *a*.

In Figs. 6 to 10 I have indicated means for centralizing the press boxes with the axial line of the press ram, such means being 115 employed in conjunction with any ordinary form of perpetual press. The main features of the feeding mechanism of the perpetual press are indicated in Figs. 6 and 7 but these are well known and do not concern my invention except as to the operation of certain parts. The centralizing means consists in securing to the baler ram 15 a bracket 16 connected at its free end by a pin 17 to a chain 18 passing at the right hand end over 125 a chain pulley 19, the opposite end of the chain passing over a chain pulley 20 mounted upon a shaft 21 and flanked at each side by screwed extensions 22 one of which has a left hand and the other a right hand 130

thread. It will be obvious that as the baler ram 15 reciprocates the chain will follow its reciprocations and so rotate the chain wheels and screws. On the bottom and outer end 5 of each press box is fixed a stud 23 carrying a roller 24 to act in conjunction with the screws 22. When the press boxes are rotated by hand the roller engages with one of the screws depending upon which way 10 the boxes are moved and entering the thread the box is drawn into axial line with the ram, the roller finally getting into the angular groove 25 between the screws 22. When the ram is withdrawn the press box 15 may be moved out of the central position by 15 pressing it in either direction so as to engage the roller 24 with one of the screws which will then move the boxes about their central pivot, the full rotary motion being afterward completed by hand. To assist in keeping the press boxes in axial line with the ram I also secure to the end of each press box a projecting stud 26 operating in conjunction with two catches pivoted to the frame *a* 20 at 27 as will be seen from Fig. 8. Each of the catches is provided with a handle 28 and with a bent inner arm 29 the extreme end of which normally bears against a stop 30 against which it is held by a spring 31. 25 Each arm 29 has an inclined face 29^a. When the press box is being moved into position the stud 26 engages the inclined face of one of the arms 29 forces it inwardly about its pivot 27 against its spring until the box 30 reaches the central position when the arm is returned by the spring and the stud is held between the inner bent ends of the two arms. Before rotating the press boxes the required 35 pivot catch is operated by drawing the handle 28 outwardly and arm 29 inwardly to free the stud 26 and allow the roller 24 being engaged with one or other of the screws in the manner previously described.

Instead of the chain wheel and screw device hereinbefore described I may arrange 40 on the underside of each press box a grooved plate or a series of plates 32 as shown in Fig. 10 such plates leaving a central track 33 and branch tracks 34 with which a roller 45 45 engages, such roller being carried by a longitudinal bar (not shown) connected to the baler ram and reciprocated by it as in the case of the chain previously referred to, the press box being pushed in one or other 50 direction to engage with the roller 35 and so move the box into central position or toward one side in the same manner as described in connection with the chain gear.

Another feature of my invention consists 55 in means for automatically stopping the feeding of material by the perpetual press when the required density of the material being compressed has been reached, such means comprising a plunger head 36 60 slideable within the press head *d* and normally

projecting within the box. The plunger has a shank or spindle 37 passing through the head into engagement with the free end (or coupled to the free end) of a short armed lever 38 mounted upon a shaft 39 70 passing to the outside of the press head and having mounted upon it a long armed lever 40 whose upper end is in engagement with a spring 41 which can be adjusted to any required resistance by the set screw and lock-nut 42. The perpetual press of known construction has normally connected with it a 75 slideable rod 43 which moves backward and forward in the well known way. This rod has mounted upon it an adjustable stop 44 80 projecting in line with the upper end of the lever 40. When, therefore, the required density of material has been reached in the press box, the plunger 36 is pushed into a 85 position with its outer end flush with the press head and in doing so the upper end of the lever 40 is moved against the influence of the spring 41 so that when the slideable rod 43 is drawn backward the projection 44 upon it will engage the lever 40, lift 90 the rod and stop the usual feeding mechanism. The rod 43 is connected with the feeding mechanism in any approved way, and it is drawn backward or reciprocated by means of an arm 44^a connected to one end 95 of it. The arm 44^a is connected to a link 44^b, which is coupled to a rod 44^c, which is connected to any longitudinally reciprocating part of the machine, such as the bar 44^d. 100

In Figs. 4 and 5 I have indicated the combination with the revolving press boxes of hydraulic pressing means for effecting the final compression of the material, such means comprising a cylinder 44ⁱ, a ram 45 105 a press head *y* and lashing plate *g*, the cylinder being suitably supported and connected to pillars 47 which in accordance with my invention are carried forward toward the center of the machine in U-shaped 110 form for the purpose of providing bearings 48 within the pillars for the head of the press *d* blocks 49 being arranged at the open side of the pillars to form the other side of the bearing. In other respects the arrangement of the boxes is as already described. 115

In Figs. 6 and 7 I have also indicated a somewhat similar form of hydraulic press arrangement in combination with the revolving boxes, similar letters herein indicating corresponding parts. The press cylinder in this case is held in position in the main frame *a* of the apparatus. At the opposite end of the complete apparatus including the perpetual press already referred to I provide any usual construction of hydraulic pump 50 which is operated by ordinary gear from the perpetual press itself, the pump being connected with the usual 120 125 130

feed and return pipes 51 with the ram cylinder. In Figs. 6 and 7 I have also indicated the central press box head provided with ball bearings at the underside to enable the boxes being moved around easily.

What I claim and desire to secure by Letters Patent is:—

1. In a baling press a plurality of press boxes mounted upon and rotatable about 10 a fixed axis, means for inclosing the sides of the boxes, a feeding box for the material to be pressed located at one side of the axis on which the boxes are mounted, a plurality of central abutments in the rotatable 15 boxes against which the material is to be pressed and a press follower arranged at the opposite side of the press boxes to that at which the feeding box is located.

2. In a baling press a plurality of press 20 boxes mounted upon and rotatable about a fixed axis, means for inclosing the sides of the boxes, a feeding box for the material to be pressed located at one side of the axis on which the boxes are mounted, a plurality 25 of central abutments in the rotatable boxes against which the material is to be pressed, press pillars bent into U-shaped form at one end to constitute bearings in which the press head can revolve, blocks secured to the 30 pillars at their open side to form part of said bearings and a press follower arranged at the opposite side of the press boxes to that at which the feeding box is located.

3. In a baling press a plurality of press 35 boxes mounted upon and rotatable about a fixed axis, a feeding box for the material to be pressed located at one side of the axis on which the boxes are mounted, a plurality of central abutments in the rotatable boxes 40 against which the material is to be pressed, doors hinged to the central press head of the press boxes themselves and catch devices comprising open frames pivoted to the boxes at the opposite ends to the hinges for 45 the covers, co-acting levers and links coupled to the open frames and to the press box lids respectively for locking the doors in position and a press follower arranged at the opposite side of the press boxes to 50 that at which the feeding box is located.

4. In a baling press a plurality of press boxes mounted upon and rotatable about an axis, said boxes being located between a feeding box at one side and a press follower 55 at the other, means for moving said boxes into axial line with the press ram or follower comprising a chain mounted upon chain wheels adapted to be reciprocated from the perpetual press feeding mechanism, right and left hand screws forming part of one of the chain wheels and a roller carriage by each press box adapted to engage with one or other of the screws, said mechanism also assisting in moving the 60 press boxes laterally from the central posi-

tion ready to have their complete rotation effected by hand.

5. In a baling press a plurality of press boxes mounted upon and rotatable about an axis, said boxes being located between a 70 feeding box at one side and a press follower at the other, means for holding the press boxes in axial line with the press ram or follower comprising a stud secured to each press box adapted to operate spring-controlled pivoted arms or catches so as to move one of said catches about its pivotal point out of the way as the boxes reach their central position, the catch returning to initial position after the passage of the 75 stud so as to hold the latter in the required position in conjunction with the second catch, and means for operating the catches by hand to enable the boxes to be turned about their supporting center when required.

6. In a baling press a plurality of press boxes mounted upon and rotatable about an axis, said boxes being located between a feeding box at one side and a press follower 90 at the other, operating arms projecting over the press box doors when the latter are closed said arms being pivoted to the press frame and provided with short arms bearing against said frame when the arms are 95 turned about their pivots to withdraw the holding means out of the press box when moved away from the press box doors to admit of the latter being opened for the discharge of the bale.

7. In a baling press a plurality of press boxes mounted upon and rotatable about an axis, said boxes being located between a feeding box at one side and a press follower at the other, means for compressing 105 the material comprising two pairs of toggle levers, the inner ends of one pair being pivoted to the follower while the inner ends of the other pair are pivoted to the frame of the press, a central right and left hand 110 screw mounted in bearings and carrying nuts to which the outer ends of both toggle levers are coupled, means for driving the screw from a power source comprising a gear wheel on the power driven shaft, a 115 wheel on the screw, carrier wheels gearing with each other and with the wheels on the shaft, screw and links movable about the shaft and screw carrying the pins upon which the carrier wheels are mounted so as 120 to keep the train of wheels in constant gear during the operation of the press, means for supporting the rear end of the follower and the toggle arms comprising a base sliding in the main frame of the press and one or 125 more rollers carried by the base to reduce friction.

8. In a baling press a plurality of press boxes mounted upon and rotatable about an axis, said boxes being located between a 130

- feeding box at one side and a press follower at the other, means for automatically stopping the feeding mechanism of the perpetual press when the required density of 5 press material has been attained, comprising a plunger in each press box adapted to coöperate with adjustable spring controlled lever mechanism operating in conjunction with an adjustable part carried by 10 the usual reciprocating rod of the perpetual press feeding mechanism.
9. In a baling press press pillars bent into U-shaped form at one end to form bearings in which the press head can revolve and blocks secured to the pillars at their open 15 side to form part of said bearings.

In testimony whereof I have hereunto set my hand in the presence of two witnesses.

HUGH IORWERTH ROBERTS.
